UNITED STATES PATENT OFFICE.

WILLIAM H. PERRY, OF CONCORD, NEW HAMPSHIRE.

DESIGN FOR A MONUMENT.

SPECIFICATION forming part of Design No. 24,866, dated November 5, 1895.

Application filed October 2, 1895. Serial No. 564,459. Term of patent 7 years.

To all whom it may concern:

Be it known that I, WILLIAM H. PERRY, a citizen of the United States, residing at Concord, in the county of Merrimac and State of New Hampshire, have invented and produced a new and original Design for Monuments, of which the following is a specification, reference being had to the accompanying drawing.

The leading features of this design relate to the shaft, its ornamental corners, its cap, and the character of finish of the several parts, as fully set forth and described in the following specification and claim, and clearly illustrated in the accompanying drawing, reference being had to the drawing by figures and letters, as follows: The base is oblong and has four vertical sides 1, terminating in an obtuse frustum of a pyramid 2, joining the sides of the pedestal, which has four vertical sides 3, terminating in an acute frustum of a pyramid 4, on one or more sides of which is placed a raised tablet 5. The shaft has four vertical sides 6, one or more of which are provided with a depressed tablet 7, having rectangular beveled edges 8 and provided in its center with a tablet 9, of similar form and flush with the tablet 7, the same being distinguishable by a border-line 10, within which the finish is of a different character. The corners of the said shaft,

and also the upper horizontal edges which adjoin the cap, are ornamented, respectively, by rustic work 11 and 12, made to represent a portion of a tree with a portion of its bark 35 and the short portion of its branches as having been trimmed off. The vertical corners 11 are represented as being secured to beveled corners 13 of the shaft.

The ornamental strips 12 are provided near 40 each end with lines 14, crossing each other, so as to represent straps or bands.

Above the ornaments 12 the cap appears in the form of an acute frustum 15, the lower edge of which is ornamented by rectangular vertical projections 16, having flat tops 17, and the top of said cap is further ornamented by a raised tablet 18, having a finish of a different character.

The various styles of finish are denoted by 50 letters of reference, A standing for rock-work, B for hammered-work, and C for polished work.

What I claim is—

The design for a monument, substantially 55 as herein shown and described.

In testimony whereof I affix my signature in presence of two witnesses.

WILLIAM H. PERRY.
